SUPERHEATER ELEMENT FOR
SMOKE-TUBE BOILERS

Herbert Frank, Cassel-Wilhelmshöhe, Germany,
assignor to The Superheater Company, New
York, N. Y.

Application January 24, 1935, Serial No. 3,220
In Germany May 19, 1933

13 Claims. (Cl. 122—462)

This invention relates to a superheater element which is intended for use in a flue of a fire-tube boiler and consists of a plurality of parallel or practically parallel tubes or portions of tubes 5 connected with one another in such a manner as to form a continuous path in which the steam flows to and fro. The object of the invention is to increase the superheating capacity of the superheater so as to increase correspondingly the superheating temperature of the steam, without any undesired fall of pressure of the steam in the superheating elements and loss of draught in the flues of the boiler.

If, as has generally been customary up to now, 10 it is endeavored to obtain an increase of the superheating temperature solely by an increase of the superheating surface, the loss of draught is increased if the diameter of the flues or the number of the same remains the same as before. In 15 order to obviate this it would be necessary to increase either the sectional area of the gas passage, that is to say, the diameter of the flues, or the number of these tubes which, however, would in either case entail difficulties in view of the restricted space available in fire-tube boilers, for 20 instance those of locomotives.

In order to pay regard to the increase of the specific volume of the steam that takes place when the steam is superheated, it has already 25 been proposed to increase the sectional area of the steam passage in the superheating tubes from the entrance end to the exit end of the same, and also the reverse way has been proposed, viz. to decrease said sectional area from the entrance 30 end to the exit end in order to increase thereby the speed of the steam.

Still another proposal is this to give the superheating tubes a smaller sectional area in that zone where the smoke gases are hottest, the intention being to increase the speed of the steam in this zone and to obtain an improved transmission of the heat from said gases to the steam. A thus designed superheating element consists, therefore, of a portion having a large sectional 40 area in that zone of the flue where the temperature of the smoke gases is comparatively low, and of a portion having a smaller sectional area in that zone where the temperature of the smoke gases is highest, this portion comprising preferably a plurality of narrow tubes.

All those proposals have, however, not proved suitable for the purpose in view, as the respective designers had failed to discover the only successful solution of the problem. This solution 45 forms the subject matter of the present invention.

This invention resides in the discovery that in order to obtain the higher superheating temperature intended it is requisite to provide for a certain correct relation between the sectional area of the steam passage, the superheating surface and the sectional area of the smoke passage. The invention contemplates obtaining this relation in such a manner that, without any material increase of the superheating surface a suitable distribution of this surface, and of the sectional area of the steam passage in the flue and at the same time an accommodation of the speed of the steam to the changes of the temperature of the smoke gases, is rendered possible.

Now, the invention resides in that the superheating element, as regards the sectional area of its steam passage, is subdivided into three zones, viz. a first zone having a large sectional area, a second zone following immediately said first zone and having a materially smaller sectional area 10 and being at least twice subjected to the action of the smoke gases streaming through the flue in that zone thereof where said gases are hottest, and a third zone having a large sectional area 15 and serving chiefly for conducting away the superheated steam. Besides this, a particular feature of the whole is that the individual zones of the element are so arranged in the flue that the free sectional area of the gas passage remains either practically the same along the entire length of the flue or increases only a little in the direction of the smoke gases, the transition portions between the different sectional areas being located either in the plane of section of the flue or where there are reversing bends of the superheating tube 20 25 30 35 within the flue.

My invention is illustrated diagrammatically and by way of example on the accompanying drawing on which Figure 1 is an axial section through a flue provided with a superheating element designed according to this invention, this element being shown in side-view, and Figures 2, 3, 4 and 5 are similar representations showing four modifications, all as fully described hereinafter.

In the constructional form illustrated in Figure 1, the numeral 2 denotes the flue, the right-hand end of which communicates with the smoke-chamber, in the upper portion of which the steam chest (not shown) is located from which the wet steam is distributed to the various superheating elements, whereas the left-hand end of the flue communicates with the fire-box. The wet steam passes first through the tube portion 1 which has a sectional area as large as possible. The steam passes then in the same direction 45 50 55

tion through the tube portions 3 and 4, in each of which the sectional area is smaller than that of the tube portion 1. Now the direction of the steam is reversed, in fact a plurality of times, 5 in that it flows now through two loops 5 having a still further reduced sectional-area. From these loops the steam flows through consecutive tube portions 6, 7 and 8, the sectional areas of which are, however, no further decreased, but are, on 10 the contrary, increased; the sectional area of the tube portion 8 through which the superheated steam is conducted away being as large as possible.

In Fig. 2 the tube portions 10 and 14 correspond practically with the tube portions 1 and 8 of Fig. 1, and the tube portion 11 corresponds practically with the tube portion 4 but between the tube portions 10 and 11 of Fig. 2, the steam path is formed by two tubes or tube portions 9 20 which are connected up in parallel to the tube portion 10, as well as to the tube portion 11. The united sectional areas of said tubes 9 of the first section is smaller than the sectional area of the tube portion 10 thereof, and the sectional area of the tube portion 11 of the intermediate section is smaller than the combined sectional area of the tubes 9, thus corresponding with the tube portions 3 and 4 of Fig. 1. The loops 12 of Fig. 2 and the tube portions 13 and 14 of the 30 third section in Fig. 2 correspond practically with the loops 5 and the tube portions 6, 7 and 8 of Fig. 1, as regards their sectional area.

In Fig. 3 is shown a constructional form intended especially for small flues. The subdivision of the steam path is in this modification extended not so far as in Figs. 1 and 2, in that there is only one loop 27 located between the tube portions 29 and 28. The two tube portions 26 correspond practically with the tube portions 1 and 8 of Fig. 1, but they are longer; they may have equal sectional area, which, however, is to be larger than that of the loop 27 and of the tube portion 28 which may likewise be regarded as a loop. The sectional area of the tube portions 29 and 28 is smaller than that of the tube portions 26, and the sectional area of the loop 27 is smaller than that of said tube portions 29 and 28, always in accordance with the principle of the invention.

In Fig. 4 the subdivision of the steam path is as in Fig. 3 also less than in Figs. 1 and 2, but while in Fig. 3 the loop 27 is formed of only one tube or tube portion there are in Fig. 4 several loops 25 connected up in parallel to parallel tube portions 23 and 24. The parallel portions 23 of the first section communicate with the entrance tube portion 21 and the parallel portions 24 of the third section communicate with the delivery tube portion 22 thereof. These end portions 21 and 22 may have equal sectional areas. Also the tubes 23 have equal sectional areas, as have also the loops 25 and the tubes 24, the sectional area of said loops 25 being the smallest of the superheating element. The loops 25 are located in that zone of the flue where the fire gases are hottest.

Finally, in Fig. 5 the wet steam supplied to the superheating element passes first through two parallel pairs of comparatively short tubes, each pair comprising in turn two parallel tubes 15 and 16, the united sectional area of which is less than the sectional area of the supply tube. Said tubes 15 and 16 are located in the proximity of the exit end of the flue. At their other end said tubes communicate with two tubes or loops 17 and 18 each having a sectional area which is

smaller than that of the appertaining pair of tubes 15 or 16, and said tubes or loops 17 and 18 communicate at their other ends with a loop 19, the sectional area of which is larger than that of the loops 17 and 18 together. Finally, the superheated steam is conducted away through the tube 20 which has the largest sectional area of all members constituting this superheating element.

As shown in the drawing the transitions from one section of a superheater element to another section may be located in the flues at the places where the direction of the steam flow is reversed; or as shown for example in Figure 3 the transitions between the sections 27, 28 and 28, 26 respectively are located in alignment with each other and substantially in the same sectional plane or transverse section through the flue. As a result of these arrangements as variously shown in the several modifications, the free sectional area of the gas passage remains practically the same over the length of the flue or increases only a little progressively in the direction of the gas flow to the exit end of the flues. Preferably the transitions between the several sections of a superheater element are made in slight steps for retaining the pressure drop of the steam as small as possible.

In order to respond to the requirement to make the fall of pressure of the steam within the superheater as small as possible it is desirable to make the sectional area of the steam passage at the exit end of the superheating tube, where the specific volume of the steam is the greatest, larger than the sectional area of the steam passage at the entrance end of said tube. However, constructive considerations render it advisable in many cases to make the sectional area at the entrance to, and the exit from, the steam passage equally large. The change of the sectional area of the steam passage may take place in the individual zones either in several abrupt steps, as shown in the drawing, or gradually along the same. Furthermore, the tubes in the individual zones or sections may be individual ones (as shown in all zones in Figures 1 and 3 or as 12, 13, 14, Figure 2 or 19, 20 Figure 5) or may comprise a plurality of tubes connected up in parallel, (as at 9 in Figure 2, 23, 25, 24 in Figure 4, or at 15, 16, 18 in Figure 5). Finally, it is advantageous for the purpose in view to provide at the place of the hottest fire gases a larger heating surface presented by tubes with the smallest sectional area for the steam passage.

It should be noted that with superheating elements designed according to this invention, the sectional area of the gas passage in the flue remains either practically the same along the entire length of the flue or increases only immaterially in the direction to the smoke chamber. Consequently, the sudden reduction of the speed of the gas current that would otherwise occur within the flue is obviated and also the risk of the formation of a deposit of soot and flue dust at this place is considerably diminished. If the speed of the gas current in the direction to the smoke chamber becomes lower, that is to say, if it is highest at the firebox, then this will be most favorable for the heat transmission, as just at this place the largest superheating surface is located through which the steam flows with the highest speed. There is, furthermore, obtained in the flues an average hydraulic depth considering the length of the tube that is essentially equal to the hydraulic depth of the heating tubes.

If one endeavors to obtain the higher superheating of the steam merely by an increase of the superheating surface, as has previously been done, then the hydraulic depth in the flues will be considerably smaller than that in the heating tubes. With equal loss of draught in two bundles of tubes the speed of flow depends only upon the hydraulic depth, in consequence whereof the heating gases are deflected in a greater measure to those flues, which are devoid of superheating tubes, and the improvement of the superheating hoped for takes place either not at all or only in a very slight measure. Besides, with great differences between the hydraulic depths of the smoke tubes and the heating tubes, the temperatures of the waste gases in these tubes are very different whereby the efficiency of the boiler is, of course, reduced.

However, by making use of a superheating element designed according to the present invention the over-all efficiency of the superheater is improved. This is true especially of so-called small-tube superheaters, that is to say, of superheaters for boilers with flues of a smaller diameter. The improvement of the over-all efficiency is, in such a case, rendered possible on the one hand by the improvement of the ratio of the heating surfaces located in the proximity of the firebox (this ratio of heating surfaces being that between the superheating surface and the evaporative heating surface) and on the other hand by the improvement of the ratio used in equipping the flues with superheating tubes (ratio between the number of the flues and the number of the heating tubes). By the term "over all efficiency" I mean the result attained by properly relating the ratio of the heating surfaces to the ratio between the flues and the heating tubes, that is to say, those tubes which have superheating tubes and those tubes which have no superheating tubes. Owing to the favorable distribution of the steam speed along the path of the superheated steam, flues of a smaller diameter can be used.

I claim:—

1. A superheater element for use in a flue of a smoke tube boiler comprising a plurality of interconnected, parallelly disposed tubular portions of different diameters extending forwardly and backwardly in the flue and constituting an inlet section, an outlet section and an intermediate section of smaller diameter than both said inlet and outlet sections and having the greater part thereof located in that part of the flue which lies adjacent the fire-box, the tubular portions constituting the superheater element being positioned with respect to each other in the flue to locate certain contiguous tubular portions of different diameters parallel to other tubular portions having diameters so related to those of said certain portions as to offset changes in the diameter of said element along the flue.

2. A superheater element for use in a flue of a smoke tube boiler comprising a plurality of interconnected, parallelly disposed tubular portions of different diameters extending forwardly and backwardly in the flue and constituting an inlet section, an outlet section and an intermediate section of smaller diameter than both said inlet and outlet sections and having the greater part thereof located in that part of the flue which lies adjacent the fire-box, the tubular portions constituting said sections of said superheater element being so disposed in the flue that certain contiguous tubular portions of diameters differing in one sense are positioned parallel to other con-

tiguous portions of diameters differing in the opposite sense and so related to the diameters of said certain portions as to offset changes in the diameter of said element along the flue.

3. A superheater element for use in a flue of a smoke tube boiler comprising a plurality of interconnected, parallelly disposed tubular portions of different diameters extending forwardly and backwardly in the flue and constituting an inlet section, an outlet section and an intermediate section of smaller diameter than both said inlet and outlet sections and having the greater part thereof located in that part of the flue which lies adjacent the fire-box, the said sections of the superheater element being so positioned with respect to each other in the flue and the diameters of contiguous portions of different diameters being so related to the diameters of other tubular portions parallel thereto that the aggregate cross-sectional area of parallelly disposed tubular portions is substantially the same at all points along the flue to provide a gas passage of substantially the same free cross sectional area along the flue.

4. A superheater element as recited in claim 1 characterized by the fact that the intermediate section includes at least one pair of parallelly disposed tubular portions that are interconnected by a return bend located in alignment with the transition between said intermediate section and one of said other sections and which have diameters so related to the tubular portions that are contiguous at said transition as to offset the change in the diameter of said element at said transition.

5. A superheater element for use in a flue of a smoke tube boiler comprising a plurality of interconnected, parallelly disposed tubular portions of different diameters extending forwardly and backwardly in the flue and constituting an inlet section, an outlet section and an intermediate section of smaller diameter than both said inlet and outlet sections and having the greater part thereof located in that part of the flue which lies adjacent the fire-box, certain of said sections consisting of a plurality of contiguous portions of different diameters positioned in the flue to locate the transitions between certain of said portions in alignment with the transitions between other tubular portions that are parallel thereto and which have diameters so related to those of said certain contiguous portions as to offset the change in diameter of said element between said contiguous portions at said transition.

6. A superheater element as recited in claim 5 characterized by the fact that said intermediate section includes pairs of parallelly disposed tubular portions that are interconnected by return bends at least one of which is located in alignment with the transition between certain contiguous tubular portions of different diameters and the tubular portions extending to and connected by said one return bend having diameters so related to the diameters of the tubular portions that are contiguous at said transition as to offset the change in the diameter of said element at said transition.

7. A superheater element as recited in claim 5 wherein the intermediate section consists of parallelly disposed tubular portions of different diameters interconnected by return bends, with the return bend between at least one pair of its tubular portions located in alignment with the transition between certain contiguous tubular

portions of said element that are of different diameters and the diameters of said pair of tubular portions being so related to the diameter of tubular portions which are contiguous at said 5 transition as to offset the change in diameter of said element at said transition.

8. A superheater element as recited in claim 1 in which at least one of said sections thereof comprises a plurality of contiguous portions forming 10 a single steam path and having cross-sectional areas of different sizes increasing in diameter with respect to the direction of gas flow through the flue.

9. A superheater element as specified in claim 15 1 further characterized by the fact that each of its sections comprises a plurality of portions having cross-sectional areas of different sizes, contiguous portions of the inlet section decreasing in diameter and those of the intermediate and 20 outlet sections increasing in diameter, all with

respect to the direction of steam flow through the superheater element.

10. A superheater element as specified in claim 1 further characterized by the fact that said first section thereof comprises a plurality of tubes connected up in parallel to said intermediate section. 5

11. A superheater element as recited in claim 1 further characterized by the fact that two of the three aforementioned sections thereof comprise a plurality of parallel tubes connected to 10 the other section.

12. A superheater element as specified in claim 1 further characterized by the fact that said first and said intermediate sections thereof each comprise a plurality of parallel tubes communicating 15 with said last section of said element.

13. A superheater element as specified in claim 1 in which said intermediate section thereof has the largest heating surface.

HERBERT FRANK. 20
